UNITED STATES PATENT OFFICE.

FRANK H. VICK, JR., OF NEW YORK, N. Y.

COMBINED MATCH-BOX AND CIGAR-CUTTER.

SPECIFICATION forming part of Letters Patent No. 752,130, dated February 16, 1904.

Application filed February 5, 1903. Serial No. 142,058. (No model.)

To all whom it may concern:

Be it known that I, FRANK H. VICK, Jr., a citizen of the United States, residing at New York, in the county and State of New York, have invented new and useful Improvements in a Combined Match-Box and Cigar-Cutter, of which the following is a specification.

This invention relates to an improvement in combined match-boxes and cigar-cutters, and has for one of its objects the production of a simple and efficient device of this character in which the cut is effected by the closing of the box-cover and in which that portion of the head of the cigar cut off is prevented from falling into the box.

With this and other objects in view the invention consists in certain combinations and constructions, as will be hereinafter fully described and then specifically pointed out in the claims hereunto appended.

In the accompanying drawings, which form a part of this specification, and in which like characters of reference indicate the same parts, Figure 1 is a side elevation of a device constructed in accordance with the invention and showing the box open; and Fig. 2 is a sectional view of the device shown in Fig. 1, but with the box closed.

Referring to the drawings, 3 indicates a receptacle for matches or other articles. This receptacle may be of any suitable form, but, as shown, is of the type usually found in match-boxes designed to be carried in a pocket. As shown, the receptacle 3 is provided with a hinged cover 4, which is held in open or closed position by means of a spring 5 in the usual manner.

The receptacle 3 and the cover 4 are each provided on one of their respective walls with a cutting edge, the edges coöperating during the closure of the box to sever an article placed between them. While these edges may be formed by beveling the walls, the cover-wall closing down outside of the receptacle, as shown, I prefer to form the cutting edge on the receptacle-wall by beveling the edge of a strip

of metal 6, secured to the inside of the receptacle-wall, and by beveling the wall of the cover, so that during the closure of the box a shearing cut is produced and the outside of the cover and of the receptacle lie in the same plane.

In some cases it has been found that coöperating curved cutting edges produce a cleaner cut than the straight type and do not injure the cigar-wrapper. Preferably, therefore, the receptacle 3 is provided with a cutting edge curved at 7 and the cover 4 is provided with a cutting edge curved at 8.

It is desirable that the head cut off the cigar fall outside the box. In the present construction this is effected by placing the cigar across the open mouth of the receptacle so that the head protrudes beyond the cutting edges. As shown, the receptacle 3 is provided with a recess 9 in the wall opposite that carrying the cutting edge. Similarly the cover 4 is provided with a recess 10 in the wall opposite that carrying its cutting edge. These recesses are arranged to register when the box is closed, thus forming an aperture in which the cigar lies during the cutting operation and through which the cigar may be withdrawn after the cutting has been effected, as is clearly illustrated in Fig. 2.

It is to be understood that the invention is not to be limited to the precise construction shown, as the construction may be varied without departing from the invention.

What is claimed is—

1. The combination with a match-receptacle having a cutting member formed on the edge of one of its walls and a recess in the opposite wall, of a hinged cover having a cutting edge on one of its walls and a recess in its opposite wall, said cutting edge coöperating with said cutting member to sever an article resting in said recesses and lying across said walls of said receptacle.

2. The combination with a match-receptacle having a curved cutting member on one of its walls and a recess in the opposite wall, of a

hinged cover having a curved cutting edge on one of its walls and a recess in its opposite wall, said cutting edge coöperating with said cutting member to sever an article resting in said recesses and lying across said walls of said receptacle.

In testimony whereof I have signed my name

to this specification in the presence of two subscribing witnesses.

FRANK H. VICK, JR.
